United States Patent

Des. 240,334

Patented June 22, 1976

240,334

MICROFILM PROJECTOR OR THE LIKE

Richard J. Olson, Pittsford, N.Y., assignor to Eastman
Kodak Company, Rochester, N.Y.

Filed Feb. 3, 1975, Ser. No. 546,639

Term of patent 14 years

Int. Cl. D16—02

U.S. Cl. D16—14

FIG.1

FIG.2

FIG.3

FIG.4

FIG.5

FIG. 6

FIG. 7

FIG. 8

FIG. 1 is a top, front and right perspective view of a microfilm projector or the like showing my new design with the top cover in the open position and the carriage in the extended position;

FIG. 2 is a top, back and right side perspective view thereof;

FIG. 3 is a top view of the microfilm projector shown in FIGS. 1 and 2 with the top cover in the closed position and the carriage in the retracted position;

FIG. 4 is a left side elevational view thereof;

FIG. 5 is a bottom plan view thereof;

FIG. 6 is a front elevational view thereof;

FIG. 7 is a rear elevational view thereof; and

FIG. 8 is a right side elevational view thereof.

I claim:

The ornamental design for a microfilm projector or the like, as shown and described.
